DESIGN FOR A VENDING MACHINE

Wallace A. Jenkins, Lakewood, Ohio, assignor to
The Atlas Manufacturing and Sales Company,
Cleveland, Ohio

Application July 28, 1947, Serial No. 140,558

Term of patent 7 years

(Cl. D52—3)

To all whom it may concern:

Be it known that I, Wallace A. Jenkins, a citizen of the United States, residing in the city of Lakewood, county of Cuyahoga, and State of Ohio, have invented a new, original, and ornamental Design for a Vending Machine, of which the following is a specification, reference being had to the accompanying drawing, forming a part thereof.

Figure 1 is a front view of a vending machine showing my new design;

Figure 2 is a rear view thereof; and

Figure 3 is a top plan view.

The sides of the casing are plain and unornamented.

I claim:

The ornamental design for a vending machine, substantially as shown and described.

WALLACE A. JENKINS.
